UNITED STATES PATENT OFFICE.

ERNST PFENNINGER, OF ODELL, ILLINOIS.

ADJUSTMENT FOR EMBROIDERING-MACHINE NEEDLES.

Application filed September 9, 1921. Serial No. 499,372.

To all whom it may concern:

Be it known that I, ERNST PFENNINGER, a citizen of Switzerland, residing at Odell, in the county of Livingston, State of Illinois, have invented certain new and useful Improvements in Adjustments for Embroidering-Machine Needles; and I do hereby declare the following to be a full, clear, and exact description of the invention, such as will enable others skilled in the art to which it appertains to make and use the same.

This invention relates to new and useful improvements in embroidering machines and particularly to the needle mountings therefor.

One object of the invention is to provide means for locking certain needles in withdrawn position so that they will not interfere with the other needles.

Another object is to provide a needle holding block which is so formed that it may be easily locked in needle operating position or in needle inoperative position.

Other objects and advantages will be apparent from the following description when taken in connection with the accompanying drawing.

In the drawing:

Figure 1 is a top plan view of a section of a needle bank of an embroidering machine, embodying the present invention, certain needles being withdrawn.

Figure 2 is an end view of the same.

Figure 3 is a vertical sectional view longitudinally of the inner locking bar.

Figure 4 is a sectional view taken on a line longitudinally of the needle holding block, showing the manner in which the locking bars retain said blocks.

Figure 5 is a fragmentary perspective view of the needle adjusting bar.

Referring particularly to the accompanying drawing, 10 represents a rail which has mounted on its upper edge the horizontal forwardly projecting plate 11. Formed in the upper face of this plate 11, and extending through the front and rear edges thereof, are the dove-tail grooves, resulting in the intermediate dove-tail ribs 13, the grooves being represented by the numeral 12. Slidable in these grooves 12 are the blocks 14, each carrying a longitudinally extending needle 15, whose point is arranged to be extended beyond the outer edge of the plate 11, when the blocks are slipped along the

grooves, and to lie wholly within the grooves when the blocks are slipped back into the grooves. Formed transversely in the upper and lower faces of each block 14 are the grooves 16 and 17, the former being disposed forwardly of the latter, and below the same.

Formed longitudinally of the plate 11, and through the outer and inner end portions of the upper and lower faces of the ribs 13, are the grooves 18 and 19, respectively, and seated in the grooves are the longitudinal bars 20 and 21, respectively. The upper face of the bar 20 is formed with a plurality of transverse notches 22 which are arranged to register with the adjacent ends of the grooves 12, when said bar is slipped in one direction, to permit the needle blocks 14 to be moved into needle extending position. In this position of the blocks 14 the grooves 16 are in alignment with the groove 18 so that when the bar 20 is slipped back to its original position, the projections 23, between the notches 22, will enter the said grooves 16, and thus hold the needle blocks against any movement in the grooves 12. When, however, the bar 20 is moved to permit the block 14 to be slipped to the rear end of the groove 12, and with the rear end face of the block in the same plane as the rear face of the plate 11, the rear groove 17 will be in alignment with the rear groove 19 of the plate 11, so that the bar 21 may be moved to engage its projections 24 in the grooves 17 of the blocks, and thus hold the blocks in such position. The needles of the blocks thus withdrawn into the grooves, will lie within the grooves 12, with their points inwardly of the front edge of the plate 11.

Each of the bars 20 and 21 is provided with means for clamping the same to the plate 11, so that they will firmly hold the blocks 14 against movement in the grooves 12. The bar 20 has upwardly extending threaded pins 27 which ride in grooves or slots 26 in the plate 11, and in the upper wall of the opening or groove 18, thumb nuts 25 being engaged on the upper ends of the pins to clamp down on the plate 11, and thus hold the same against sliding movement. The bar 21 is formed with longitudinal slots 28 which receive upwardly extending pins 29, carried by the plate 11, enlargements 30 being provided on the pins to clamp down on the bar, and hold the latter against sliding movement.

In view of the fact that the rail 10, in

actual practice, is from thirty to forty-five feet in length, it would be a laborious process to shift the individual needles in or out, and to obviate this I provide the bar 31, which has a plurality of regularly spaced screws 32 engaged transversely therethrough, and a second plurality of regularly spaced screws 33, arranged at right angles to the screws 32, and intermediate the same. 10 In setting the bar for use, the proper screws, corresponding to the needles which it is desired to move out into operative position, on the rail 10, are driven through the bar so that their unheaded ends will project from 15 the corresponding face of the bar. The bar is then applied to the blocks 14, with the said projecting ends of the screws 32 within narrow grooves 34 of the blocks, and moved, bodily, in a direction toward the outer edge 20 of the rail 10, with the result that the desired needles are projected from the rail, into operative position. The other screws 33 are properly adjusted, in the same manner as the screws 32, but at different intervals, so that other groups, or needle blocks, at corresponding intervals, may be moved in or out. By this arrangement, it is possible to project the needles at the desired intervals for producing the stitching necessary for the embroidered design. This is clearly shown in Figures 4 and 5, the former showing the bar in operative position, while the latter shows the bar in fragmentary perspective view. 30 By this construction, when it is desired to use certain needles and discontinue the use of the remainder thereof, those which are not to be used are positively held in such position as to offer no interference. 35 What is claimed is:

1. An embroidering machine needle de-

vice including a main block having a plurality of transverse grooves in one face, needle holding blocks slideable in said grooves and each having a groove in its upper face, the main block having a longitudinal groove in its upper face intersecting the transverse grooves, and a locking bar slideable in the longitudinal groove and having projections on its lower face for engagement in the grooves of the needle blocks to hold the blocks against movement in the transverse grooves. 45

50

2. An embroidering machine needle device including a main block having a plurality of transverse grooves in one face and a longitudinal groove in its upper face adjacent one edge thereof and a longitudinal opening adjacent the opposite edge, said longitudinal groove and opening intersecting the transverse grooves, a needle block slideable in each of the transverse grooves and having transverse grooves in its upper and lower faces adjacent its opposite ends respectively and adapted for alignment with the longitudinal groove and opening respectively, a locking bar slideable in the longitudinal groove and having transverse passages in its lower face resulting in intermediate projections the latter being arranged to enter the upper grooves of the needle blocks, and a locking bar slideable in said opening and having transverse passages resulting in intermediate projections arranged to enter the lower transverse 60

grooves of the needle blocks.

In testimony whereof, I affix my signature, in the presence of two witnesses.

ERNST PFENNIGER.
